CLAIM

The ornamental design for a scope ring alignment assembly, as shown and described.

DESCRIPTION

FIG. 1 is a front-top-left perspective view of a scope ring alignment assembly showing my new design;

FIG. 2 is a front-top-left perspective view of a scope ring alignment assembly attached to a firearm;

FIG. 3 is a right elevation view thereof;

FIG. 4 is a left elevation view thereof;

FIG. 5 is a top elevation view thereof;

FIG. 6 is a bottom elevation view thereof;

FIG. 7 is a front elevation view thereof; and,

FIG. 8 is a rear elevation view thereof.

The broken line showing of the arbor, the holes in the centering component and the barrel, the firearm, the marking and the knobs on the centering component in FIGS. 1-8 are included for the purpose of showing environmental structure and form no part of the claimed design.
